RAILWAY TRACK CIRCUIT APPARATUS

Andrew J. Sorensen, Edgewood, Pa., assignor to
The Union Switch & Signal Company, Swiss-
vale, Pa., a corporation of Pennsylvania

Application September 22, 1939, Serial No. 296,117

7 Claims. (Cl. 246—34)

My invention relates to railway track circuit apparatus, and particularly to apparatus for track circuits using coded direct current.

Railway track circuits have been proposed which use time spaced impulses of direct current with the individual impulses of relatively high peak voltage and short duration as compared with the duration between successive impulses. The high peak voltage serves as an aid to the shunting sensitivity of the track circuit and the short duration serves to limit the output of the current source to a relatively low energy level. In such track circuits code following track relays are provided for controlling the signaling circuits. It has been found that when adverse train shunting conditions prevail due to rusty rail surfaces, light-weight high speed trains and other operating conditions, a few impulses of current of sufficient magnitude to operate the track relay may reach a relay now and then past the poor train shunt with the result that a proceed signal indication may be falsely established for an interval.

Accordingly, a feature of my invention is the provision of novel and improved apparatus for track circuits of the type here contemplated wherewith the display of a proceed signal indication is not effected until the track relay has responded to several successive impulses of the track circuit current. Another feature of my invention is the provision of novel and improved apparatus for track circuits of the type here involved which is selectively responsive to both the polarity and magnitude of the voltage of such track circuit current impulses. Other features and advantages of my invention will appear as the specification progresses.

I shall describe one form of apparatus embodying my invention, and shall then point out the novel features thereof in claims.

In the accompanying drawing, Fig. 1 is a diagrammatic view showing a preferred form of apparatus embodying my invention. Figs. 2 and 3 are diagrams illustrating operating characteristics of the apparatus of Fig. 1.

Referring to Fig. 1, the reference characters 1a and 1b designate the track rails of a stretch of railway track which rails are formed by the usual insulated rail joints 2 into consecutive track sections of which sections only the one full section W—X and the adjoining ends of the two adjacent sections are shown for the sake of simplicity. Each track section is provided with a track circuit comprising a source of coded direct current connected across the rails at one end of the section and a code following relay connected with the rails at the other end of the section.

The source of coded direct current for the track circuit of section W—X comprises a battery 5, a code transmitter CT and a track transformer

XT. The code transmitter CT may take the form of any one of the several well-known structures for such devices and it is sufficient to point out that as long as the operating winding 6 of code transmitter CT is supplied with current from any convenient source (not shown) a contact member 7 is operated at a preselected code rate, such as, for example, 75 operation cycles per minute.

The contact member 7 alternately engages a normal contact 8 and a reverse contact 9 each 10 operation cycle. The interval required for movement of the contact member 7 between the two contacts 8 and 9 is short and only a small portion of the operation cycle, and the interval contact member 7 engages either contact 8 or 9 is 15 one-half the operation cycle interval less the interval required for contact member 7 to move between its two positions. The contact member 7 and the associated contacts 8 and 9 are used to control the supply of current from battery 5 to 20 the track transformer XT. When contact member 7 engages normal contact 8, current is supplied from battery 5 to the left-hand half portion of primary winding 10 of transformer XT and when contact member 7 engages reverse contact 9, current is supplied to the right-hand half portion of primary winding 10 as will be apparent by an inspection of Fig. 1. A condenser 13 may be connected across the primary winding 10 to 25 improve the operation.

A secondary winding 11 of transformer XT is connected across the rails according to traffic conditions in advance of section W—X. A mid terminal of secondary winding 11 of transformer XT is connected with rail 1b over wire 12. The rail 1a is connected with either the right-hand or the left-hand terminal of secondary winding 11 according to different traffic conditions in advance of the section. To be explicit, the left-hand terminal of secondary winding 11 is connected with rail 1a over wire 13, a back contact 14 of a relay XR1 to be later described, and wire 15; while the right-hand terminal of secondary winding 11 is connected with rail 1a over wire 16, front contact 17 of relay XR1 and wire 15.

It is to be seen, therefore, that each time either contact 7—8 or 7—9 of code transmitter CT is closed direct current flows in either the left-hand or the right-hand portion of primary winding 10 and magnetic energy is stored in transformer XT, 50 and each time either contact 7—8 or 7—9 is opened the current is interrupted and the magnetic energy decays. The circuit including primary winding 10 is so proportioned as to its time constant that the magnetic energy builds up in 55 transformer XT slower than it decays so that a relatively low voltage electromotive force is induced in secondary winding 11 while the magnetic energy is building up and a relatively high voltage electromotive force is induced in the sec- 60

ondary winding 11 when the magnetic energy decays. Consequently, when front contact 17 of relay XR1 is closed connecting the right-hand portion of secondary winding 11 with the rails of section W-X, a high voltage current impulse is supplied to the rails each time contact 7-8 or 7-9 is opened, and a low voltage current impulse is supplied to the rails each time either contact 7-8 or 7-9 is closed. The parts are so arranged that when relay XR1 is picked up closing front contact 17 the high voltage current impulses supplied to the track rails of section W-X are of positive polarity and the low voltage current impulses are of negative polarity. This characteristic of the current impulses is illustrated by the graphs of Fig. 2. When relay XR1 is released closing back contact 14 to connect the left-hand portion of secondary winding 11 across the rails of section W-X, the high voltage current impulses are of negative polarity and the low voltage current impulses are of positive polarity as illustrated by the graphs in Fig. 3. Furthermore, as illustrated in Figs. 2 and 3 each individual high voltage current impulse is of short duration as compared to the duration between such successive impulses. Also, it is to be observed that a high voltage current impulse is followed immediately by the next succeeding low voltage current impulse because the time required by contact member 7 to move from engagement with one contact 8 or 9 into engagement with the other contact is short.

It is to be seen, therefore, that when traffic conditions in advance of section W-X are such as to cause relay XR1 to be picked up in a manner to later appear, code impulses of direct current of the pattern illustrated by Fig. 2 are supplied to the track circuit of section W-X, and when the traffic conditions in advance are such as to cause relay XR1 to be released code impulses of direct current of the pattern illustrated by Fig. 3 are supplied to the track circuit of section W-X.

The track circuit for section W-X is provided with two code following relays WCF and WTC whose respective operating windings 18 and 19 are connected in parallel across the rails at the end W of the section. The relay WTC is preferably of the direct current polar type characterized by its polar armature remaining in the last position to which it was moved when the relay becomes deenergized. That is to say, contact members 20 and 21 of relay WTC remain in the position to which they were last moved when the operating winding 19 of the relay is deenergized. Relay WTC is so arranged that when winding 19 is energized by current of positive polarity its contact members 20 and 21 are moved to the right-hand position as viewed in Fig. 1 to engage the respective contacts 24 and 25, and when winding 19 is energized by current of negative polarity the contact members 20 and 21 are moved to the left-hand position as viewed in Fig. 1 to engage contacts 22 and 23, respectively. Relay WTC is further so proportioned as to be effectively energized and operated in response to both the high and low voltage current impulses supplied to the track circuit of section W-X in the manner explained hereinbefore. The relay WCF may be of the direct current polar type characterized by the fact that its contact members 26 and 27 are biased to engage respective left-hand contacts 28 and 29 when the relay is deenergized as well as when operating winding 18 of the relay is energized by current of

negative polarity. When winding 18 of relay WCF is effectively energized by current of positive polarity the contact members 26 and 27 are operated to engage right-hand contacts 30 and 31, respectively. Relay WCF is further so proportioned and adjusted that it is effectively energized to operate its contact members 26 and 27 to the right-hand position by the high voltage current impulses of positive polarity supplied to the track circuit but not by the low voltage current impulses of positive polarity.

Consequently, when traffic conditions are such as to cause relay XR1 to be picked up so that the current impulses supplied to the track circuit of section W-X are of the code pattern illustrated by Fig. 2, that is, a high voltage positive impulse and a low voltage negative impulse each operation cycle, the code following relay WTC is operated to its right-hand position by each current impulse of positive polarity and to its left-hand position by each current impulse of negative polarity. The code following relay WCF is operated to its right-hand position by each current impulse of positive polarity and is operated back to its left-hand position by the biasing element of the relay when the current impulse of positive polarity ceases, the biasing element being aided, of course, by the energization of relay WCF by the low voltage current impulse of negative polarity. When traffic conditions are such as to cause relay XR1 to be released so that the track circuit of section W-X is supplied with current impulses of the code pattern illustrated by Fig. 3, that is, a high voltage negative impulse and a low voltage positive impulse each operation cycle, the code following relay WTC is operated in step with the impulses as before, but the code following relay WCF is held inactive at its left-hand position.

I have found that when code following relay WTC is of the type and adjustment here proposed, it is operated to its two positions for substantially equal periods in response to the code patterns here proposed, and in addition the operation periods are practically of the same length regardless of changes in ballast resistance caused by wet or dry conditions with the result that practically uniform operation of the decoding apparatus to be shortly described controlled by the code following relay is assured.

The code following relays WCF and WTC are used to control two decoding relays WR1 and WR3, while relay R1 controls in turn a repeater relay WR2. Relays WR1, WR2 and R3 are preferably of the direct current type, relay WR1 being provided with a relatively long predetermined slow pick-up period, say, for example, 3 seconds; relay WR2 being provided with a slow release period of say, for example, 3 seconds, and preferably with a slow pick-up period also; and relay WR3 being provided with a slow release period sufficient to span from one high voltage current impulse of the track circuit to the next.

Relays WR1, WR2 and WR3 are here used to control the operation circuits of a wayside signal WS which governs traffic through the section W-X, and also to control the supply of code impulses of current to the track circuit for the section next in the rear of section W-X. The wayside signal WS may be any one of the standard three-position type of signals and is here shown as a color light signal having a green lamp 32, a yellow lamp 33 and a red lamp 34 for displaying clear, approach and stop signal indi-

cations, respectively. The relay WR1 controls at its front contact 17a and back contact 14a the supply of current to the track circuit for the section next in the rear of section W—X in the same manner that relay XR1 controls at its front contact 17 and back contact 14 the supply of current to the track circuit of section W—X. 5

It is believed that the circuits and the manner whereby code following relays WCF and WTC 10 control the relays WR1, WR2 and WR3, and the control effected by these latter relays can best be understood by a description of the operation of the apparatus of the track circuit for section W—X. At the start it is to be observed that repeater relay WR2 is controlled over a simple circuit including back contact 35 of relay WR1 and consequently relay WR2 is energized and picked up at the end of its slow pick-up period when relay WR1 is released closing back contact 35, and 15 relay WR2 is deenergized and released at the end of its slow release period when relay WR1 is picked up opening back contact 35.

Assuming that relay XR1 is picked up so that current impulses of the code pattern illustrated 20 in Fig. 2 are supplied to the track circuit of section W—X and section W—X is unoccupied, code following relays WTC and WCF are both operated to the right-hand position by each high voltage current impulse of positive polarity, relay 25 WTC is operated to its left-hand position by each low voltage impulse of current of negative polarity and relay WCF is operated to its left-hand position by its biasing element subsequent to each of such high voltage current impulses. Hence, 30 relays WTC and WCF are both operated at a rate corresponding to the code rate of the current impulses supplied to the track circuit.

When relay WTC is operated to its right-hand position closing contact 20—24, direct current is 40 supplied over either one of two alternative circuits to the top half portion of a primary winding 36 of a decoding transformer WDT. One of such circuits includes terminal B of any convenient source of direct current such as a battery not shown, front contact 37 of repeater relay WR2, wire 38, contact 20—24 of relay WTC, top half portion of primary winding 36 of transformer WDT and terminal C of the same source of current. The other alternative circuit extends from terminal B over back contact 39 of relay WR2, front contact 40 of relay WR1, wire 38, and thence as before traced. Each time relay WTC is operated to its left-hand position closing contact 20—22, direct current is supplied to the 45 lower half portion of primary winding 36 over the above traced alternative circuits, as will be apparent by an inspection of Fig. 1. It is to be noted that a condenser 41 is preferably connected across the primary winding 36 to improve the 50 operation. It follows that an electromotive force having a frequency corresponding to the rate at which relay WTC is operated is induced in the secondary winding 42 of transformer WDT.

The secondary winding 42 of transformer WDT 55 is connected with relay WR1 over a circuit having two alternative paths one of which can be traced from a mid terminal of secondary winding 42 over wire 43, winding of relay WR1, contact 21—25 of relay WTC and to the lower outside 60 terminal of secondary winding 42; and the other of which paths can be traced from the mid terminal over wire 43, winding of relay WR1, contact 21—23 of relay WTC, contact 26—28 of relay WCF and to the upper outside terminal of 65 secondary winding 42. It is clear, therefore, that 70

the electromotive force induced in secondary winding 42 due to the operation of relay WTC is rectified and relay WR1 is energized by the unidirectional current supplied thereto. Repeater relay WR2 is now deenergized and released because relay WR1 is picked up opening back contact 35. 5

With code following relay WCF operated to periodically close contact 27—31, current impulses are supplied to relay WR3 over a simple 10 circuit and that relay is effectively energized and picked up, relay WR3 remaining picked up from one impulse to the next by virtue of its slow release period.

With relays WR1 and WR3 picked up and relay WR2 released a signal circuit is completed from terminal B over lamp 32, front contact 47 of relay WR3, back contact 44 of relay WR2, front contact 45 of relay WR1 and to terminal C, and lamp 32 is illuminated so that signal WS 20 displays a clear indication. It is to be noted that front contact 17a of relay WR1 is now closed so that the current impulses supplied to the track circuit for the section next in the rear will be of the code pattern illustrated in Fig. 2. 25

Assuming next that relay XR1 is released so that the code impulses supplied to the track circuit of section W—X are of the code pattern illustrated by Fig. 3 and section W—X is unoccupied, the code following relay WTC is operated the 30 same as before but code following relay WCF remains inactive at its left-hand position. Again, the operation of code following relay WTC causes unidirectional current to be supplied to relay WR1 through the decoding transformer WDT so 35 that relay WR1 is picked up and repeater relay WR2 is released. Relay WR3 is now deenergized and released because code following relay WCF is inactive and held at its left-hand position. 40

With relay WR1 picked up and both relays WR2 and WR3 released, a signal circuit is completed from terminal B over lamp 33, back contact 46 of relay WR3, back contact 44 of relay WR2, front contact 45 of relay WR1 and to terminal C, and lamp 33 is illuminated causing signal WS to display an approach indication. It is to be noted that front contact 17a of relay WR1 is still closed so that the track circuit for the section next in the rear is still supplied with current impulses of the code pattern illustrated in Fig. 2. 45

Assuming next that a train occupies section W—X to shunt the track circuit so that code following relays WTC and WCF are inactive, relay WCF is held at its left-hand position by the biasing element of the relay and relay WTC is held at once or the other of its two positions. No current is now supplied to relay WR1 and that relay is released with the result that the repeater 55 relay WR2 is energized and picked up at the end of its slow pick-up period. Relay WR3 is also released because relay WCF is inactive. 60

With relays WR1 and WR3 released and repeater relay WR2 picked up, a signal circuit is 65 completed from terminal B over lamp 34, back contact 35 of relay WR1 and to terminal C, and lamp 34 is illuminated to cause signal WS to display a stop indication. Since relay WR1 is released closing back contact 14a the current impulses supplied to the track circuit for the section next in the rear are of the code pattern illustrated by Fig. 3. 70

It is to be observed that when a train enters section W—X to shunt the track circuit, relay 75

WR¹ is released almost immediately opening the circuit to the primary winding 36 of decoding transformer WDT, and opening the clear signal circuit and closing the stop signal circuit. With 5 relay WR¹ released so that repeater relay WR² is energized and picked up at the end of its slow pick-up period to close the other alternative circuit for supplying current to the primary winding 36, it follows that as soon as current impulses 10 again are supplied to code following relay WTC to operate that relay the decoding relay WR¹ is at once supplied with unidirectional current through the decoding transformer. However, if the train shunt is poor and one or two current 15 impulses reach relay WTC strong enough to operate that relay, the relay WR¹ is not picked up unless a number of successive impulses sufficient to span the slow pick-up period provided for relay WR¹ flow past the train shunt to operate the code 20 following relay WTC. Furthermore, should a sufficient number of current impulses flow past the train shunt so that the decoding relay WR¹ is picked up, neither the approach nor clear signal circuit is closed until the end of the slow release 25 period of repeater relay WR² and relay WR² is released closing back contact 44. It follows, therefore, that if the track circuit current impulses have a code rate of, say, 75 per minute, the relays WR¹ and WR² can readily be adjusted 30 so that five or six or even more successive current impulses are necessary to restore the apparatus and complete either the approach or clear signal circuit.

It should be observed that relay XR¹ which 35 controls the supply of current to the track circuit of section W—X is itself controlled by the code following relays XCF and XTC of the track circuit next in advance of section W—X in the same manner that relay WR¹ is controlled by the 40 code following relays WCF and WTC of the track circuit for section W—X. Consequently, when the section next in advance is unoccupied, relay XR¹ is picked up to cause current impulses of the code pattern of Fig. 2 to be supplied to the track 45 circuit of section W—X and establish a clear signal indication for signal WS. When the section next in advance is occupied, relay XR¹ is released to cause current impulses of the code pattern of Fig. 3 to be supplied to the track circuit of section 50 W—X and establish an approach signal indication for signal WS.

An advantage of apparatus embodying my invention is that the display of a proceed signal indication due to a loss of train shunt such as may 55 ordinarily occur because of rusty rail surfaces or other operating conditions is avoided. Also, code following relays of the type here provided give a selective response to both the polarity and voltage code conditions of the track circuit current impulses. Also, as stated hereinbefore, such code following relays give substantially equal so-called "on" and "off" operating periods.

Although I have herein shown and described only one form of apparatus embodying my invention, it is understood that various changes and modifications may be made therein within the scope of the appended claims without departing from the spirit and scope of my invention.

Having thus described my invention, what I 70 claim is:

1. In combination, a track section, a source of direct current, a transformer having a secondary winding connected across the rails at one end of said section, a code transmitter including a contact member having a predetermined operation

cycle to open and close a contact each said operation cycle, means including said contact to connect said direct current source with a primary winding of said transformer for supplying to the rails of said section a high voltage impulse of 5 current of a selected polarity each time said contact is opened and a low voltage impulse of current opposite in polarity to said selected polarity each time said contact is closed, a polar code following relay connected with the rails at the other 10 end of said section operated when alternately energized by said current impulses of said selected polarity and said opposite polarity, another code following relay connected with the rails at said other end of the section biased to a first position 15 and operated to a second position only when energized by said high voltage current impulses of said selected polarity, and decoding relay means controlled jointly by said two code following relays. 20

2. In combination, a track section, a source of direct current, a transformer having a secondary winding connected across the rails at one end of said section, a code transmitter including a contact member having a predetermined operation 25 cycle to open and close a contact each said operation cycle, means including said contact to connect said direct current source with a primary winding of said transformer for supplying to the rails of said section a high voltage impulse of current of a selected polarity each time said contact is opened and a low voltage impulse of current opposite in polarity to said selected polarity each, time said contact is closed, a first and a second code following relay connected with the rails at 30 the other end of said section, said first relay operated to a first and a second position in step with said current impulses of said selected and opposite polarities, said second relay biased to a first position and operated to a second position 40 only by said high voltage current impulse of said selected polarity, a slow pick-up relay, a slow release repeater relay controlled over a back contact of said slow pick-up relay, circuit means including a first position and a second position 45 contact of said first code following relay for supplying unidirectional current to said slow pick-up relay, another slow release relay controlled over a second position contact of said second code following relay; and a signaling circuit including a front contact of said slow pick-up relay, a back contact of said repeater relay and a front contact of said other relay. 50

3. In combination, a track section, a source of direct current, a transformer having a secondary 55 winding connected across the rails at one end of said section, a code transmitter having a contact member operated at a predetermined rate, means including said contact member to connect said source of direct current with a primary winding of said transformer for supplying to the rails of said section impulses of current of a code rate corresponding to said predetermined operation rate of said contact member, a code following relay connected with the 60 rails at the other end of said section respectively energized by each of said current impulses for operation of the relay at said code rate, a slow pick-up relay, a slow release repeater relay controlled over a back contact of said slow pick-up 70 relay, decoding means controlled by said code following relay when operated for supplying current to said slow pick-up relay, and a signaling circuit including a front contact of said slow pick-up relay in series with a back contact of said 75

repeater relay for displaying a signal only when said code following relay is operated by a pre-selected number of successive impulses of current supplied to the rails.

5 4. In combination, a track section, a source of direct current, a transformer having a secondary winding connected across the rails at one end of said section, a code transmitter having a contact member operated at a predetermined rate, 10 means including said contact member to connect said source of direct current with a primary winding of said transformer for supplying to the rails of said section impulses of current of a code rate corresponding to said predetermined operation rate of said contact member, a code following relay connected with the rails at the other end of said section effectively energized by each of said current impulses for operation of the relay at said code rate, a slow 15 pick-up relay, a slow release repeater relay controlled over a back contact of said slow pick-up relay, decoding circuit means supplied with current either over a front contact of said repeater relay or over a back contact of said repeater relay in series with a front contact of said slow pick-up relay, and said circuit means controlled by said code following relay when operated for supplying current impulses to said slow pick-up relay, a signal, and a circuit including a back 20 contact of said repeater relay in series with a front contact of said slow pick-up relay to operate said signal only when said code following relay is operated by successive current impulses of a number predetermined by the interval 25 30 formed by the pick-up period of said slow pick-up relay plus the release period of said repeater relay.

5 5. In combination, a track section, a source of direct current, a transformer having a secondary winding connected across the rails at one end of said section, a code transmitter having a contact member operated at a predetermined rate, 40 means including said contact member to connect said source of direct current with a primary winding of said transformer for supplying to the rails of said section impulses of current of a code rate corresponding to said predetermined operation rate of said contact member, a code following relay connected with the rails at the other end of said section effectively energized by each of said current impulses for operation of the relay at said code rate, a slow pick-up relay, a slow release repeater relay controlled over a back contact of said slow pick-up relay, 45 a decoding transformer, a circuit including either a front contact of said repeater relay or a front contact of said slow pick-up relay and controlled by said code following relay when operated for supplying impulses of direct current to a primary winding of said decoding transformer to induce electromotive forces in the secondary winding of that transformer, another circuit for applying said electromotive forces to said slow pick-up relay to effectively energize that 50 relay, a first signal circuit including a back contact of said slow pick-up relay, and a second signal circuit including a front contact of said slow pick-up relay in series with a back contact of said repeater relay whereby said first signal circuit is closed immediately after said two rails of said section are shunted and said second signal circuit is closed only after said code following relay has been operated by a 55 60 65 70

predetermined number of successive impulses of current.

6. In combination, a track section, a source of direct current, a code transmitter having a contact member operated at a predetermined rate, 5 circuit means including said contact member and controlled by traffic conditions in advance of said section for supplying to the rails of the section from said current source current impulses of a first or a second code according to a first or 10 a second traffic condition in advance, said first code comprising alternate high voltage impulses of current of positive polarity and low voltage impulses of current of negative polarity, said second code comprising alternate high voltage 15 impulses of current of negative polarity and low voltage impulses of current of positive polarity, a polar code following relay connected with the rails of said section effectively operated to a first and a second position in response to the 20 polarity of said code impulses of current, another code following relay connected with the rails of said section biased to a first position and effectively operated to a second position in response to said high voltage impulses of current of positive polarity only, a first decoding 25 relay controlled over a first and a second position contact of said polar code following relay and a first position contact of said other code following relay, a second decoding relay controlled over a second position contact of said other code following relay, and signal circuits 30 selectively controlled by said first and second decoding relays.

7. In combination, a track section, a source of direct current, a code transmitter having a contact member operated at a predetermined rate, 35 circuit means including said contact member and controlled by traffic conditions in advance of said section for supplying to the rails of the section from said current source current impulses of a first or a second code according to a first or a second traffic condition in advance, said first code comprising alternate high voltage impulses of current of positive polarity and low voltage impulses of current of negative polarity, said second code comprising alternate high voltage 40 impulses of current of negative polarity and low voltage impulses of current of positive polarity, a polar code following relay connected with the rails of said section effectively operated to a first and a second position in response to the 45 polarity of said code impulses of current, another code following relay connected with the rails of said section biased to a first position and effectively operated to a second position in response to said high voltage impulses of current of positive polarity only, a slow pick-up relay controlled over a first and a second position contact of said polar code following relay, a slow 50 release repeater relay controlled over a back contact of said slow pick-up relay, another slow release relay controlled over a second position contact of said other code following relay, a first signal circuit including a back contact of said slow pick-up relay; a second signal circuit including a front contact of said slow pick-up relay, a back contact of said repeater relay and a back contact of said other relay; and a third signal circuit including a front contact of said slow pick-up relay, a back contact of said repeater relay and a front contact of said other 55 60 65 70 relay.
